UNITED STATES PATENT OFFICE.

CHARLES A. IVES, OF BROOKLYN, NEW YORK.

PRESERVE-CAN HOLDER.

1,426,387.

Specification of Letters Patent. Patented Aug. 22, 1922.

Application filed December 19, 1921. Serial No. 523,385.

To all whom it may concern:

Be it known that I, CHARLES A. IVES, a citizen of the United States, and residing at Brooklyn, in the county of Kings and State 5 of New York, have invented certain new and useful Improvements in Preserve-Can Holders, of which the following is a specification, such as will enable those skilled in the art to which it appertains to make and use the 10 same.

This invention relates to can holder devices which are adapted to be used in connection with cans or containers of various kinds and classes for preserved fruits, vegetables and the like, and the operation of 15 opening the can by the use of the usual can opening means, and the object of the invention is to provide a device of the class specified comprising two jaw members provided 20 at one end with hand-pieces and the opposite ends of which are connected or joined by a chain or link construction, whereby the separate parts of the device are permanently connected; a further object being to provide 25 means cooperating with said chain or link construction for adjusting the position of said jaw members one from another; and with these and other objects in view the invention consists in a device of the class and 30 for the purpose specified which is simple in construction and efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

40 Fig. 1 is a perspective view showing one use of my improved can holding device; and, Fig. 2 a detail plan view of the device.

Heretofore it has been customary in the operation of opening a tin can containing 45 preserved food products and the like to grasp the can in one hand, or to bear down upon the top portion of the can with one hand, preferably the left hand of the operator, while inserting and moving a can opener about the periphery of the top portion of the can as indicated in Fig. 1, this procedure is always dangerous and has resulted in serious accidents to the operator, said operator being cut by the partially sheared portion of

the can and by the slipping of the opening 55 device.

My invention consists in providing means whereby the can may be firmly held in a predetermined position in the operation of opening such can with the usual can opener, 60 and in Fig. 1 of the drawing, I have shown for illustrative purposes a can 5 the top 6 of which is adapted to be opened by a suitable can opening device 7 partially indicated in said figure, and at 8 I have shown my improved holding device, said device comprising 65 separate similarly formed jaw members 9.

The jaw members are preferably stamped from sheet metal and comprise an approximate semi-circular portion 10 at one end of which is a handle member 11 which extends at an angle to the semi-circular portion 10 and the other end of which is provided with an aperture 12. In practice, a chain or link 70 member 13 composed of a plurality of separate links 14 is secured to one of the jaw members 9 by a loop 15 passed through the aperture 12 in the end of said jaw member, and the other end of said chain is provided 75 with an attaching device 16 comprising a loop which passes through the aperture 12 in the other of said jaw members, and said attaching device is also provided with a hook-shaped portion 17 which is adapted to pass 80 through the loops of the links 15 of the chain, or the loop 15 in adjusting the relative position of the jaw members 9 to one another.

The inner faces of the jaw members 9, or 90 the semi-circular portions thereof, are provided with teeth or projections 18 which are adapted to grasp and firmly hold a can or the like in the use of the device.

In using the device for holding a can, as 95 shown in Fig. 1 the separate jaw members are adjusted, as hereinbefore set out, whereby the device may grasp and hold a can or the like of predetermined dimensions, or as shown in Fig. 1 of the drawing the chain 100 may be fully extended or the full capacity of the device used, and said chain and jaw members 9 are passed around the can and the handle members 11 are forced together by one hand of an operator, as clearly shown in 105 Fig. 1 of the drawing, to firmly grasp and hold the can in predetermined position. It will be understood that the grasping device

may be moved about the can circumferentially thereof at intervals in the operation of opening the can by simply releasing the pressure on the handle members 11 and shifting the device on said can.

While I have shown and described the device as specifically designed for use in holding cans of the class described containing preserved fruits, vegetables, soups, milk and the like, it will be understood that the device may also be used in opening screw caps or closure devices of Mason jars and the like, and it will also be apparent that while I have shown certain details of construction for carrying my invention into effect, that I am not necessarily limited to these details and various changes therein and modifications thereof may be made, within the scope of the appended claims, without departing from the spirit of my invention or sacrificing its advantages.

Having fully described my invention, what I claim as new and desire to secure by Letters Patent, is:—

1. A can holding device of the class described comprising two similar sheet metal jaw members, said jaw members comprising semi-circular portions provided at one end with handle members projecting at an angle thereto and the other ends of said semi-circular portions being provided with apertures, a chain the ends of which are passed through the apertures of said jaw members

for securing said jaw members together, and a hook-shaped device at one end of the chain 35 and adapted to be detachably connected with the separate links of the chain for adjusting the relative position of said jaw members.

2. A can holder of the class described comprising two similar jaw members, said jaw members being provided at one end with handle members, means for permanently and adjustably connecting the other ends of said jaw members, the ends of said jaw members being apertured, a chain the ends of which 40 pass through the apertures of said jaw members for permanently connecting the same and one end of said chain being provided with a catch device adapted to engage the separate links of the chain for adjusting the 45 relative position of said jaw members.

3. A can holder of the class described comprising two similar jaw members, said jaw members being provided at one end with handle members and at the other end thereof 50 with apertures, a flexible member the ends of which are secured in the apertures of said jaw members, and means at one end of said member adapted to engage predetermined portions of the flexible member for adjust- 55 ably connecting said jaw members.

In testimony that I claim the foregoing as my invention I have signed my name this 17th day of December, 1921.

CHARLES A. IVES.
